E. N. SWAN & A. BEIGHTOL.
AUTOMATIC FIRE LIGHTER.
APPLICATION FILED MAR. 18, 1912.

1,048,372.

Patented Dec. 24, 1912.

UNITED STATES PATENT OFFICE.

EARL NORRIS SWAN AND ALTON BEIGHTOL, OF SCOTIA, CALIFORNIA.

AUTOMATIC FIRE-LIGHTER.

1,048,372.

Specification of Letters Patent. Patented Dec. 24, 1912.

Application filed March 18, 1912. Serial No. 684,428.

To all whom it may concern:

Be it known that we, EARL N. SWAN and ALTON BEIGHTOL, residing at Scotia, in the county of Humboldt and State of California, 5 have invented a new and Improved Automatic Fire-Lighter, of which the following is a specification.

This invention relates to that class of appliances, especially designed for lighting 10 the fuel in the fire chambers or boxes of ranges, stoves, fireplaces and the like, and it primarily has for its purpose to provide a device of the general character stated, of a simple and economical construction, that 15 can be easily applied to or removed from a stove, heater, fire-place or other place where a lighting device is needed.

Our invention comprises a carrier or support for holding a match or matches, a heating 20 element in the nature of a holder for supporting the head of a match that forms a part of an electrical circuit and which, when the circuit is energized serves to ignite the match.

25 Our invention, in its more subordinate nature, embodies the peculiar construction and novel arrangement of parts, all of which will be hereinafter explained, specifically pointed out in the appended claims and 30 illustrated in the accompanying drawing, in which:

Figure 1, is a perspective view that illustrates an operative arrangement of our invention. Fig. 2, is a longitudinal section of 35 a portion of an ordinary range, with our improvement applied, the latter also being shown in section. Fig. 3, is a perspective view of the match carrier, the wire connections between the "asbestos" plates being indicated in dotted lines. Fig. 4, is a cross 40 section on the line 4—4 on Fig. 3.

Our lighting appliance is automatically 45 operated through the instrumentality of an ordinary push button controlled electrical circuit, energized by the common type of batteries, and the said appliance comprises a body or carrier, composed of two non-combustible, (asbestos) plates 1—1 between which are clamped and concealed copper 50 wire sections 2—2, one end of each of which joins with the binding posts 3—3, that also form bolts for clamping the plates 1—1 together. The other ends of the wire sections 2—2 join to other binding posts 4—4 that 55 also form clamping bolts for holding the plates 1—1 solidly upon each other, and in

such a manner that the wires 2—2 are practically embedded between the asbestos members 1—1. Binding posts 3—3 connect with the terminals of a source of electric energy 60 which may be a house circuit in which is located a push button 6 located at any desired point in the house, for example adjacent the bed, as shown in Fig. 1 of the drawing, so that the fire, if desired, may be lighted 65 by the occupant of the bed, without rising.

The match holder, the peculiar construction of which forms an essential feature of our invention, consists of a heating member 70 7 or tip, in the nature of a very thin spring wire, preferably of German silver wire of 20 gage, or less, which connects with the binding posts 40 on the top of the carrier, by the clamp nuts 70. The tip member 7 75 is bent upon itself at one or more places to form U-shaped spring seats 71, for receiving the heads 80, of the parlor matches 8.

9 designates a yoke shape support for the stems 81 of the matches, and the same is 80 made of a stout German silver wire, the ends of which are bent into eyes 90, held embedded in the asbestos body by the clamp screws 10 and nuts 11. The cross bar of the arch member 9 is bent to form spring seats 85 92 to receive the ends of the match stems, as shown.

From the foregoing description taken in connection with the drawing, the advantages 90 of, and the manner in which our invention is used will be readily apparent. By reason 95 of mounting the match holder on an asbestos base and embedding the feed in sections 2—2 in the said base, the wires are protected from excessive heat. Further by mounting the match holding members in the manner shown and described the igniting tip of the wire member can be readily replaced by a new one should the same burn out. Again, the match holding body can be 100 readily applied to any part of the fire-box, or open fire-place and can be as readily removed after the fire is started.

For supporting the body 1, it may have a hanger loop 19, as shown. 105

What we claim is:

1. In a firelighter, a match holder including a heating wire having means for holding the head of a match, a source of electric energy in circuit with the match holding 110 member and a make and break device in the said source of electric energy.

2. In a firelighter, a support or body comprising a non-combustible body, a match holder mounted in the said body, said holder including a heating member having means for gripping the head of the match, a source of electric energy in circuit with the said heating member, and a push button control in the said source of electric energy.
3. In a firelighter, a match holder, comprising a non-combustible body, composed of a pair of asbestos plates clamped together, a match holder mounted in the said body, said holder including a heating member having means for gripping the match head, a source of electrical energy, a switch control in said energy, the latter including feed wire sections connected with the ends of the heating member and embedded between the asbestos plates.
4. As a new article, a firelighter comprising

ing a body consisting of two plates of non-combustible material, a pair of binding posts at each end, said posts including members that clamp the two plates together, one set of the binding posts forming connections 25 for joining the lighter with a source of electrical energy, feed wires embedded between the two plates that connect with their respective opposite binding posts, a heating wire connection that joins with the other 30 set of binding posts above the lighter body, said connection having a portion for receiving and gripping the head of a match, a support in the lighter body having a seat for holding the other end of the match.

EARL NORRIS SWAN.
ALTON BEIGHTOL.
